CLAIM

I claim the ornamental design for a geothermal U-bend socket fusion fitting, as shown and described.

DESCRIPTION

FIG. 1 is a perspective view of a geothermal U-bend socket fusion fitting, showing my new design.

FIG. 2 is a front plan view thereof.

FIG. 3 is a rear plan view thereof.

FIG. 4 is a right side plan view thereof.

FIG. 5 is a left side plan view thereof.

FIG. 6 is a top plan view thereof. The broken lines in FIG. 6 define the boundaries of the claimed design, and they and the areas within them form no part of the claimed design; and, FIG. 7 is a bottom plan view thereof.
